METHOD FOR MAKING A FORGED CLAMP

Charles S. Card, Cortland, N. Y., assignor to The
Brewer-Titchener Corporation, Cortland, N. Y.,
a corporation of New York

Application April 20, 1936, Serial No. 75,292

4 Claims. (Cl. 29—148)

This invention broadly relates to the art of so called strain clamps whose metal body is adapted to be forged in one piece and more particularly pertains to a dead end clamp for the holding of a looped transmission conductor or other cable when subjected to high mechanical tension and in which the cable grip is distributed over a considerable portion of a spirally grooved seat with the slack cable end anchored in place by keeper means.

In the present instance, a planiform, cross-sectionally V shaped groove of the incomplete annular type is resorted to in which such arcuate groove contour is preferably given a gradually decreased radius of curvature toward the slack cable end to provide for snubbing action. One such groove end may be equipped with a tangentially disposed hanger arm adapted to cooperate with a suitable insulator or the like clamp supporting member. The respective extremities of my arcuate groove are subtended by an integral bridge piece having keeper means mounted thereon.

The primary object of my improvements is to devise a simple method by which a clamp of the indicated character can be effectively forged up in successive die forming operations by first drawing a flanged cup-shaped body planchet which after centrally piercing its crown region, permits of reshaping such pierced edge of the planchet to complete an arcuate groove at the minimum of labor and other production costs.

Embodied herein are also other processing features contrived to promote the end in view and all of which aspects will hereinafter be more explicitly set forth. Reference is had to the accompanying two sheets of drawings which are illustrative of certain preferred embodiments and in which drawings:

Fig. 1 shows a plan view of my forged clamp assembly when looking axially toward a side flange of my arcuate groove, and Fig. 2 represents an end view thereof.

Figs. 3 and 4 are respectively taken along the sections 3—3 and 4—4 of Fig. 1, while Fig. 5 details the finished groove formation as taken along line 5—5.

Fig. 6 illustrates in plan, an initial deep drawn blanking operation herein resorted to prior to in-turning one of the side flanges of my arcuate clamp groove.

Figs. 7 and 8 are respectively taken along the sections 7—7 and 8—8 of Fig. 6 to define my cup shaped planchet as formed prior to shearing out its crown wall.

Referring first in detail to my clamp as an article of manufacture of the annular kind depicted in Figs. 1 to 5, this may comprise an arcuate groove component 10 having a V-shaped profile as in Fig. 5 including complementary side flanges

11 and 12. The respective marginal edges of these lips are faced outwardly and extend in substantial parallelism along the major portion of the groove length. The rounded base of each groove preferably lies in a common plane without being given any pronounced helical formation. The respective extremities of one such groove flange namely 11, may be spanned by a relatively flat, integral bridge piece 13.

The cable 14 is intended to wedgingly rest in 10 and be grippingly engaged between the groove flanges to effect the desired snubbing action. To this end, the groove bottom or seat is preferably given an oval-like contour such that the taut cable may be wrapped tangentially on its larger 15 groove radius R1 and with the slackened cable end brought radially inward to conform with the smaller radius R2. Said bridge piece may be provided with a lug or boss 15 that is apertured in a direction parallel to the axis of my arcuate snubbing groove. Complementary pairs of axially offset guide knobs such as 16 or the like ridges may be located to straddle the slack cable end for centering purposes. A depressed region may extend crosswise between each such pair of knobs 20 to provide for an undulated seat contour adapted 25 to correspondingly indent the clamped cable end.

A T shaped keeper bolt has a threaded shank 17 entered through said lug aperture and this serves to draw the clamped cable toward the bridge piece. The transversely disposed cross bar or keeper head 18 may be inclined with respect to the shank axis as in Fig. 4 and each oppositely disposed bar projection may be undercut to provide for the interchangeable dished recesses 19 30 and 20 respectively having differently sized cable receiving radii. By turning said T-head around the shank, the slack end of either a relatively 35 large or small conductor can thereby be tightly gripped and anchored to my clamp body.

Tangentially projecting from one of the groove side walls in a counterwise direction to the pull of the tensioned cable, is a hanger arm 21 of which the extremity is preferably but not necessarily, given a bifurcated formation 22 adapted to receive a conventional coupling pin 23. The described clamp may be initially supported in place and have the cable 14 drawn around its comparatively short groove, whereupon the keeper is applied to secure the tensioned cable. In order to keep the tensioned cable pull in alignment with that of the hanger arm, I preferably warp one groove end as at 10A.

Having described the structural features of my clamp design, the improved mode for forging the same may be traced by reference to Figs. 6 to 8. The billet is preferably forged to provide for a deep drawn or cup shaped body planchet such as 25 provided with a divergent hanger arm 28. In the swaging of same, its matrix or drafted die 60

blocks may be parted along the line 26, it being understood that the resulting flash therealong is to be neatly trimmed.

One side flange component of my clamp groove 5 is initiated during the forming of said planchet, as shown. The tangentially disposed forked hanger arm is simultaneously swaged up with said flange component and the bridge piece 29 provided with imprinted guide knobs or ridges 10 such as 30A, 30B, etc., together with a cooperating keeper boss 27. A feature of my forging process resides in the shaping up of a potential complementary groove side flange such as 12 of Fig. 2. In order to initially draw and gather the stock 15 required therefor, I introduce the intermediary step of forging a cross-sectionally socketed or cup shaped planchet 25 having a flared mouth or radially extended rim 31 together with a laterally reenforced flash portion that constitutes a 20 transverse crown wall 32 of the kind represented in Fig. 7. The medial region of such artificial crown wall is preferably kept relatively thick to prevent metal rupture during the required deep drawing operation, whereupon the thinner mar- 25 ginal region of said crown wall is pierced to leave a trimmed edge on the planchet along a shear line such as 33, which edge is thereupon crimped radially outward into its dotted position 34 of Fig. 7 by the use of suitable forming tools. When 30 thus shaped up, this completes my arcuate clamp groove 35, whose structural aspects correspond to the previously described similar element 10.

Subsequent to being forged as in Fig. 6, the arm fork 28 may be skewed about its longitudinal axis 35 to lie in the quadrature Fig. 1 position. For this purpose, it is preferred to reheat a localized shank region of the arm 21 and while hot, subject said region to an axial twist without warping or otherwise deforming the remainder of the completed 40 forging. Such twisting operation may be performed before or after piercing the crown wall 32.

When such cable groove is given a finite contour length and the respective ends are subtended by a unitary bridge piece, then the contiguous 45 warped skirt portion 36 of my cup shaped planchet may be kept thinner than the remainder of the skirt wall. Said thinner skirt portion may thereupon be sheared out along the circuitous path indicated in dotted outline at 40 (see Fig. 7) 50 to provide for an unobstructed groove gap adjacent to the finished bridge piece 29. This same underlying method may also be applied to the making of an endless groove, except that in such instance, the entire perimetric skirt length of my 55 cup shaped planchet is similarly crimped.

It will be observed that by virtue of my improvements, it becomes possible to forge as contrasted to casting, a one piece strain or dead end clamp that is free from hidden material flaws. 60 This requirement is particularly appropriate in connection with the installation of high tension conductor clamps because of the obvious danger that may be associated with an inadvertent dropping of a sustained transmission line. My clamp 65 also possesses a high degree of strength for a given weight and is in all respects admirably suited for the purpose intended. In addition, the forging method herein disclosed materially facilitates the economical manufacture of arcuate 70 clamp grooves on a rapid productive basis.

Other advantages will be apparent to those skilled in this art, it being understood that various

changes in the structural clamp details or the mode of shaping the side flange thereof may be resorted to in carrying out the present teachings, either with or without an integral hanger arm, all without departing from the spirit and scope 5 of my invention heretofore described and more particularly pointed out in the appended claims.

I claim:

1. The method of swaging a billet into a one piece body having a cross-sectionally V-like 10 groove including complementary side flanges each provided with an arcuate marginal edge, and which method consists in initially forging and thereby drawing a cup shaped planchet to include a rim region that is spread radially outward 15 to form one of said side flanges having a protuberance gathered thereon and the bottom of which cup shape is spanned by a crown wall, piercing said wall, and then by a crimping step reshaping the pierced wall edge of the planchet 20 to extend outwardly into substantial parallelism with the free marginal edge of said one side flange and thereby complete the aforesaid groove formation.

2. The method of swaging a billet into an annular clamp body having an arcuate groove of finite length including complementary side flanges of which the respective ends of one such flange are united by a bridge piece, and which method consists in initially forging and thereby drawing a 30 cup shaped planchet including an endless skirt wall that is spanned by a crown wall and the free rim region of which skirt wall is spread 35 radially outward to form the aforesaid one flange having an integral bridge piece extending between the terminals of said one flange, a bridge piece thereacross and the skirt piercing said crown wall and severing a portion of the skirt contiguous to the bridge piece, and then by a crimping step reshaping the pierced wall edge of the planchet 40 to extend radially outward into substantial parallelism with the free marginal edge of said one side flange to complete said groove formation.

3. The method of swaging a billet into an annular clamp body having a cross-sectionally V-like 45 groove including complementary side flanges, and which method consists in forging and thereby drawing a socketed planchet provided with a cup shaped cavity whose bottom is initially closed by a crown wall and the rim region of which cavity 50 is spread radially to form one of the aforesaid flanges together with an integral hanger arm extending tangentially therefrom, piercing the crown wall of said socket, and then by a crimping step reshaping the pierced wall edge of the 55 planchet to extend radially outward into substantial parallelism with the free marginal edge of said one side flange to complete said groove formation.

4. The method of swaging a billet into a one 60 piece body shaped to initiate a cross-sectionally V-like groove including complementary side flanges, and which method consists in hot forging and thereby drawing a socketed planchet having a cavity whose bottom wall is initially closed 65 and the rim region of which cavity is spread radially to form one of the aforesaid flanges together with integral arm means extending tangentially therefrom, and then reheating a localized medial region of said arm and axially twisting- 70 the free end region thereof.
